UNITED STATES PATENT OFFICE.

LUDWIG HONIGMANN, OF BAD TOLZ, AND FRIEDRICH BARTLING, OF MUNICH,
GERMANY.

DRYING AND GRADING PLANTS FOR GRANULAR WATER-CONTAINING MATERIALS.

Application filed June 2, 1926, Serial No. 113,287, and in Germany June 3, 1925.

This invention relates generally to well known oven plants in which granular water-containing material, such as for example moist coal, is dried by continuous working. 5 To this end use may be made for example of the known revolving ring ovens in which a ring continuously revolving within a heated muffle is charged with a thin layer of the material to be dried thus carrying it 10 through the oven chamber after which the material is carried out again in various ways. If the material is taken out in the usual manner simply by being wiped off the carrier it is received in the form of a 15 mixture of various grain sizes and mostly also in a not quite dry condition.

The object of the invention is to enable the material to be obtained in absolutely dry condition and at the same time graded 20 according to different grain sizes while in addition the utilization of the heat employed is improved and the output enlarged.

According to this invention provision is made of means, in co-operation with the 25 constantly operating drying oven, for enriching a preliminarily heated air or gas current at the delivery point of the oven with the granular material and thereafter conveying it through a series of grading and dust clearing devices in which operation, while the drying of the material by the heat of the suction air continues, the 30 coarsest down to the finest dust particles are consecutively separated.

In the ordinary continually acting drying ovens the heating gases pass away from the oven with a material remnant of useful heat. According to this invention this heat remnant is utilized for the preliminary 35 heating of the suction air which then passes to the drying material along its whole travel through the grading and dust removing device, taking up the moisture withdrawn therefrom.

To this end according to this invention, 40 use is made in front of the suction point of a heat exchanging device utilizing as heat liberating means the oven gases and as heat absorbing means the suction air.

In order to attain a grading according to 45 grain sizes the suction conduit according to this invention is provided in the rear of the suction point with consecutive pockets into which the various grain sizes of the material

are caused successively to drop commencing, 55 of course, with the coarsest grain sizes.

Following this grading device are, according to this invention, preferably a 60 number of dust removers due to the fact that at that stage the suction air still carries with it a large amount of dust-like material. In this way it is possible to obtain the drying material carried along almost entirely and properly graded according to 65 sizes so that at the end of the suction conduit the suction air passes out almost entirely free from dust.

A constructional form of the invention is by way of example diagrammatically illustrated in the annexed drawing. The installation comprises a drying oven A which in the instance shown is a simple revolving ring oven with a revolving ring rotating in a muffle on to which ring the material is charged in the form of a thin layer while 70 the oven chamber is directly or indirectly heated so that at the end of the rotation the material is discharged in as dry a condition as possible.

Connected to the drying oven A, according to this invention, is an air conduit B through which air or gas is continually drawn in the direction of the arrow f by the action of a pump F. The air first enters, at a, a heat exchanging device c of any appropriate construction and while passing through the latter from a to b acts as a heat 75 absorbing means.

The means giving off heat are the combustion gases of the oven which are conveyed therethrough from d to e. From b the suction air travels to the delivery point D of the oven and at this point it is interrupted by a jet-like device with the aid of which the suction air has mingled therewith 80 the granular material supported on the ring 85 of the oven. The dust carrying suction air now passes to the grading device E which is composed of a number of pockets e¹, e², e³ adapted to receive successively the coarsest 90 grain sizes. These grain sizes may then be discharged by the manipulation of appropriate chutes or slides. The heated air acts over the whole course of the suction air 95 through the conduit B exerting a drying 100 effect on the drying material carried thereby.

In the consecutive grading and dust removing devices the granular and dust like

material is gradually withdrawn from the air and in exchange it becomes charged with the moisture from the material. The suction air freed from the coarsest granular constituents then travels due to the action of the pump into a dust remover G of any desired construction in which the dust particles are to a large extent precipitated, collecting in the hopper shaped bottom g from which they can be withdrawn. By preference the completely freed air is brought into a further dust remover H in which even the finest dust particles are separated. At the point h the suction air finds its outlet.

15 We claim:

1. In an apparatus for drying granular water-containing materials, the combination with a drying oven; of a conduit connected to said oven at its delivery point, a heat-exchanging device connected to said oven to receive oven gases therefrom for preliminarily heating suction air passing through said device to said delivery point, and means for creating a current of said suction air past said delivery point and into said con-

duit to convey all of the material in said oven into said conduit wherein said material is dried by said current.

2. In an apparatus for drying granular water-containing materials, the combination with a drying oven; of a conduit connected to said oven at its delivery point, a heat-exchanging device connected to said oven to receive oven gases therefrom for preliminarily heating suction air passing through said device to said delivery point, means for creating in addition to the combustion gases in said oven, a current of said suction air past said delivery point and into said conduit to convey all of the material in said oven into said conduit wherein said material is dried by said current, and a dust-removing device connected to said conduit for effecting a removal of dust from said suction air.

45 In testimony whereof we have signed our names to this specification.

LUDWIG HONIGMANN.
FRIEDRICH BARTLING.
